UNITED STATES PATENT OFFICE.

ERICK LEONARD AX, OF NORTH BRADDOCK, PENNSYLVANIA.

SAFETY PLIERS.

Application filed September 11, 1920. Serial No. 409,511.

To all whom it may concern:

Be it known that I, ERICK LEONARD AX, a citizen of the United States, and resident of North Braddock, in the county of Allegheny 5 and State of Pennsylvania, have invented certain new and useful Improvements in Safety Pliers, of which the following is a specification.

This invention relates to wire cutting pliers, and has for its particular object, the provision of such pliers having safety means for holding the wire that has been cut.

Another object is to adapt such safety means to the well known and accepted form 15 of pliers now in use without materially changing their form or adding to their weight.

Still another object is to provide pliers of this class that will be strong, durable, of 20 simple construction and cheap to manufacture.

Heretofore pliers of this class have been provided with cutting notches, and have come into general use. However, oftentimes 25 the wire when cut will fly and strike either the operator or one of his fellow workmen, and many times has caused serious injury to their eyes and other parts of their bodies. Especially this is true in cutting barbed 30 wire.

With the present construction of pliers, the safety means will positively grip and hold the ends of a cut wire, thereby preventing such ends from flying and injuring 35 the operator or any of his fellow workmen.

The invention is illustrated in the accompanying drawings, in which—

Figure 1 is a side elevation of a pair of pliers in closed position, illustrating the invention.

Fig. 2 is a top plan view thereof,

Fig. 3 is a partial side elevation showing the pliers open, and

Fig. 4 is a view showing two pairs of 45 clamping pins.

Referring particularly to the drawings, the letters A and B designate the two limbs of my improved pliers, which are constructed to form gripping jaws or heads 2 having 50 serrated gripping faces 3, handle portions 4, and disk-bearing joint portions 5. The disk-bearing joint portions 5 are formed in the usual manner by forming an enlarged circular bearing disk portion between the jaw or head 2 and the handle 4 of each limb, and

cutting said disk portions away to form the usual interlocking joint, pivotally held together by a pivot pin 6.

The portions 5 are cut away to form notches 7 and 8, the inner edges of which 60 act as cutting blades to cut wire or the like, the notches 7 and 8 of the pair of limbs co-operating to form a continuous upper and lower grooves or recess for the reception of the wire to be cut.

The disk portions 5 of limbs A and B have substantially triangularly shaped slots 10 and 9, respectively, formed therein, the slot 9 having its widest opening at the rear of the jaw member 2 and converging upwardly and rearwardly, forming a small opening in the forward face of the upper notch 7, while the slot 10 has its widest opening at the forward end of the handle portion and converges upwardly and forwardly, 75 forming a small opening in the rear face of the upper notch 8.

Clamping pins 11 are mounted loosely within the slots 9 and 10, and are of sufficient length to engage the rear and front 80 faces, respectively, of the upper pair of notches 7 and 8 when the pliers are closed. The pin 11 within the slot 9 has its lower end pivotally mounted in a depression or slot 14 in the jaw portion of the limb opposite the one in which it reciprocates, and the pin 11 within the slot 10 has its lower end pivotally mounted in a depression or slot 14 in the forward end of the handle portion of the limb opposite the one in which it reciprocates.

In Fig. 4 I have shown the lower pair of notches 7 and 8 also equipped with my improved clamping means. This construction is a duplication of that already described, 95 with the exception that two slots, 9 and 10, are formed in each disk and a pin 11 is mounted in each slot so as to provide a pair of clamping pins for both the upper and lower pairs of notches 7 and 8.

The operation of the device is as follows—

Wire or the like is passed through the notches 7 and 8, which are in alinement when the pliers are in open position. Pressure is then applied to the handle portions 4, 105 and the pliers are closed, which will cause the inner or cutting edges of the notches to grip and cut the wire. Simultaneous with the cutting of the wire by closing the pliers, the clamping pins 11 will move through the 110

narrow or small end openings of the slots 9 and 10, and either engage the wire being cut, clamping it against the walls of such notches, or if the wire be of small diameter 5 the pins will pass over it and hold it from flying.

It will, of course, be understood that one or more pins may be used as desired. Either one or both pairs of notches may be equipped 10 with clamping pins to hold both ends of a cut wire, or only a single pin may be used.

If desired the pins 11 may be mounted on a spring base to accommodate large diameter 15 wire. Such construction would permit further movement of the limbs A and B upon their pivot pin 6 after the pins 11 have clamped against the wire.

It will also be understood that many other 20 modifications in design and construction of the pliers will readily suggest themselves to those skilled in the art, and may be made without departing from the spirit of my invention as defined in the appended claims.

I claim:—

- 25 1. Pliers comprising a pair of limbs pivoted together and having wire-cutting notches therein, and means for clamping both ends of the cut wire within said notches.
- 30 2. Pliers comprising a pair of limbs pivoted together and having wire-cutting notches therein, and pins adapted to clamp the wire within said notches when cut.
- 35 3. The combination with pliers comprising a pair of limbs pivoted together and having at least one wire-cutting notch therein, of a pin adapted to move into and out of said notch to hold the end of a cut wire.
- 40 4. The combination with pliers comprising a pair of limbs pivoted together and having wire-cutting notches therein, of a pin adapted to move into each of said notches as said pliers are closed to cutting position, thereby holding the cut wire, and to move

out of said notches as said pliers are moved to open position, thereby releasing said wire. 45

5. The combination with pliers comprising a pair of limbs pivoted together and having a plurality of pairs of wire-cutting notches therein, of a pair of pins adapted 50 to move into and out of each of said pairs of notches to clamp the end of the cut wire.

6. Pliers comprising a pair of limbs pivoted together, each of said limbs comprising a jaw portion, a handle portion, and a disk joint portion formed between said jaw and 55 handle portions, said disk portion of each limb being provided with wire-cutting notches, the notches of each disk being adapted to align with the notches of the other disk when the pliers are in open position, pins adapted to reciprocate through suitable slots formed in said joint disk portions and communicating with said wire-cutting notches, said pins being adapted to move into and out of said notches to hold 60 the ends of the cut wire.

7. Pliers comprising a pair of limbs pivoted together, each of said limbs comprising a jaw portion, a handle portion, and a disk joint portion formed intermediate said 70 jaw and handle portions, said disk portion of each limb being provided with wire-cutting notches, pins adapted to reciprocate through suitable slots formed in said disk portions and communicating with said 75 notches, said pins having one end pivotally mounted in the limb opposite that in which they operate, and being adapted to move into said notches as said pliers are closed to cutting position to thereby hold the cut wire 80 and arranged to move out of said notches as said pliers are moved to open position to thereby release said wire.

In testimony whereof, I have hereunto signed my name,

ERICK LEONARD AX.
